UNITED STATES PATENT OFFICE.

ARTHUR PILLSBURY DODGE, OF NEW YORK, N. Y.

CONDENSER.

SPECIFICATION forming part of Letters Patent No. 611,358, dated September 27, 1898.

Application filed December 1, 1897. Serial No. 660,414. (No model.)

To all whom it may concern:

Be it known that I, ARTHUR PILLSBURY DODGE, a citizen of the United States, residing in the city, county, and State of New York, 5 but formerly of Chicago, Illinois, have invented certain new and useful Improvements in Condensers, of which the following is a specification.

My invention relates to motor-cars for street-car use, and concerns more especially a condenser system placed in the top of the car in connection with a main and supplemental or false roof.

In the accompanying drawings, Figure 1 15 represents a cross-sectional view of the car embodying my improvements. Fig. 2 is a detail view showing the head of the condenser with the steam-pipe leading thereto. Fig. 3 is a detail view of the condenser, partly 20 in section, with the roof shown on one side. Fig. 4 is an elevation at one end of the car.

In the drawings the car A is shown with the seats B in the center thereof and facing in opposite directions. The condenser is arranged 25 below the ordinary roof of the car and extends over the spaces at the sides of the car, so as to leave sufficient head-room for the passengers. The condenser C comprises a series of inner and outer tubes D D', the 30 inner tubes being air-tubes, such as heretofore used by me in my former condenser systems, while the outer tubes are steam-tubes and communicate with the interior of head-boxes E at the ends of the car, which head-boxes are in turn connected with the exhaust 35 of the cylinders through pipes F. The inner air-tubes extend through these head-boxes to communicate with the outside air, so that the steam confined in the annular space between 40 the inner and outer tubes is subjected to the condensing influence of the air. The condenser has a central depending portion over the seats, while its side portions are higher up to provide a proper amount of space for the movement of the passengers. The condenser is placed below the plane of the ordinary roof G, and this roof may be in the form 45 of a grating or open-work to allow escape of hot air from among the outer tubes, while the main roof H, which serves as a protection 50 to the passengers against the elements, is ar-

ranged below the lower edge of the condenser and is of a shape to conform thereto—that is, its central portion depends below the plane of the side portions. This main roof serves 55 to catch the rain or snow and to direct it to a suitable drain-channel after it has acted upon the exposed tubes of the condenser. The steam-supply pipe, as shown in Fig. 2, projects into the head-box. I may provide a 60 main roof H of sectional form, one section being used on each side of the car, as shown in Fig. 3, and the condenser may be made in two sections, one for each side of the car. The water of condensation may be taken from 65 the boxes by any suitable drains, such as those shown in Letters Patent of the United States No. 585,624, dated June 29, 1897.

In Fig. 3 the condenser is shown slightly modified, it being made of one section and the main roof H being made of two sections, with an upturned flange h at the inner edge of each section, leaving a space between for the passage of air, and this space is covered by an inclined shield which will prevent the 75 fall of moisture or rain down through the opening.

What I claim as my invention is—

1. A condenser for motor-cars and the like having a central depending portion, and side 80 portions in a higher plane with tubes extending between the head-boxes and with a roof extending below the condenser, substantially as described.

2. A condenser comprising head-boxes, a 85 series of tubes connecting them and a roof below the condenser, the center of the condenser and roof being lower than the sides, substantially as described.

3. In combination in a motor-car, the seats 90 arranged centrally thereof, a condenser having a depending central portion and elevated side portions to provide head-room over the aisle, substantially as described.

4. In combination in a car having the seats 95 running longitudinally thereof, a condenser having a depending portion over the seats and elevated portions over the aisles, substantially as described.

5. In combination, the car and a condenser 100 under the ordinary roof thereof comprising head-boxes and connecting-tubes and a main

drainage-roof below the condenser, the upper car-roof being of open-work, substantially as described.

6. In combination, a condenser comprising 5 head-boxes and connecting-tubes, a roof below the condenser comprising side portions with upturned flanges at their inner edges with a space between the said flanges, and a

hood covering the said space, substantially as described. 10

In testimony whereof I affix my signature in presence of two witnesses.

ARTHUR PILLSBURY DODGE.
